(57) **CLAIM**

The ornamental design for a bottle holder, as shown and described.

DESCRIPTION

FIG. 1 is a distal front perspective view of a bottle holder having a bottle therein being worn on an arm of a person; FIG. 2 is a distal rear perspective view of the bottle holder shown in FIG. 1 with the bottle therein;

FIG. 3 is a distal rear perspective view of the bottle holder shown in FIG. 1 without a bottle;

FIG. 4 is a proximal rear perspective view of the bottle holder shown in FIG. 1;

FIG. 5 is a proximal rear perspective view of the bottle holder shown in FIG. 3 without a bottle;

FIG. 6 is a front elevation view of the bottle holder shown in FIG. 3;

FIG. 7 is a rear elevation view of the bottle holder shown in FIG. 3;

FIG. 8 is a plan view of the distal end of the bottle holder shown in FIG. 3;

FIG. 9 is a plan view of the proximal end of the bottle holder shown in FIG. 3;

FIG. 10 is a right elevation view of the bottle holder shown in FIG. 3; and,

FIG. 11 is a left elevation view of the bottle holder shown in FIG. 3.

The dot-dash broken lines in FIGS. 1-11 represent environmental subject matter that forms no part of the claim. The dash-dot broken lines in FIGS. 1-11 depict stitching.

1 Claim, 11 Drawing Sheets
